UNITED STATES PATENT OFFICE

GUY A. COUNTRYMAN, OF ASHLAND, OHIO

TOOL FOR STRAIGHTENING BENT BEAMS

Application filed June 16, 1931. Serial No. 544,781.

This invention relates to tools for straightening bent frames, axles, and bumpers of automobiles and its principal object is to provide a simple and practical tool particularly adapted to straighten I-shaped and U-shaped steel beams. The tool made according to the invention resembles in general shape and form a wrench with a fixed and movable jaw adjustable to different sized

beams, and includes means especially adapted to rigidly hold the web portion of channel and I beams flat against and parallel to the clamping surface of the movable jaw, while one flange of such beam is backed against the main body of the tool, without applying excessive and frequently deforming pressure against the flanges of the beam. Such means according to the invention consists of a short lever pivotally secured to and embedded in the rigid clamping jaw and readily adjustable to its working position if so desired. Finally, according to the invention the adjustable clamping jaw carries a pivotally mounted hook member adapted to attach the tool intermediate its ends to a support and adapt the tool to reshape bent curved beams to their original curved form, all as hereinafter more fully described in the appended specification and drawing forming part hereof and as more concisely pointed out in the appended claims.

In the drawing, Fig. 1 is a perspective view of the tool as used in a bent channel iron, Fig. 2 a side elevation of the tool, and Fig. 3 a sectional view on line 3-3 of Fig. 2. Fig. 4 is a sectional view on line 4-4 of Fig. 3, and Fig. 5 a sectional view on line 5-5 of Fig. 2. Figure 6 is a diagrammatic view showing the use of the tool in straightening the rear horn of an automobile frame, the dotted lines indicating the frame and tool after bending operations.

The tool comprises an elongated shank or body portion A formed from a preferably cast steel bar of I-shaped cross section rectangularly offset at one end to form a fixed jaw member 2. Mounted on the shank A is a movable jaw 3 formed with a hollow enlargement 4 which sleeves over the shank A, thus providing for the necessary longi-

tudinal sliding movement of the movable jaw with respect to the shank and fixed jaw 2, during clamping operations of the tool. The opposite end of shank A is threaded as at 25 to facilitate attaching thereto a handle of any desired length (not shown).

The centrally disposed web portion 4' of shank A is provided on opposite sides thereof with a series of ratchet teeth 5 offset with respect to each other which co-operate with a pair of oppositely disposed pivoted ratchet levers or pawl 6 carried by jaw 3 to hold the latter in any desired adjusted position. These pawls are mounted on pins 8, secured in ear portions 9 of enlargement 4 for pivotal movement in and out of slots 30 communicating with the ratchet teeth 5. The pawls are preferably provided with finger engaging portions 11 for manual operation thereof. A spring-pressed plunger 14 adapted to seat in a series of circular recesses 12 and thus serve as an additional locking means for the movable jaw is desirable in view of the extreme stresses to which the tool is subjected. This plunger 14 is slidably guided in a bushing 15, threadedly mounted in the opening 15' in the jaw 3, and is provided with a cut-out portion 16 to co-operate with a shoulder portion 17 on the plunger and thus permit normal engagement of the plunger with recesses 12. To effect and maintain the plunger in inoperative position, the latter is pulled outwardly and slightly turned so that shoulder 17 engages the straight edge of bushing 15.

So far the arrangement described closely resembles a wrench which may readily be applied to flat or solid iron bars, however, in using such tool for rolled bars of U or I shaped cross section there is danger of mutilating the thin flanges thereof, particularly where considerable power is applied in re-shaping sharply bent and twisted beams. To prevent such damage I provide a special lever 18 pivotally mounted, cam shaped at 19 and countersunk in a recess 20 formed in the face of a fixed jaw 2. This lever cooperates with jaw 3 in bracing the work against distorting turning stresses and out of contact with the fixed jaw. For example,

the web portion 21 of a channel member B (see Fig. 1) is held rigidly against and parallel to the clamping face of jaw 3, while at the same time the flat top flange 24 of the member is forced into engagement with that portion of the shank A of the tool between the jaws. Lever 18 is so dimensioned and its pivot point so chosen that in its working position such lever forms an angle of approximately 30° to 45° with the main body of the tool and its bearing. Lever 18 is of cam-shape so that spring-pressed plunger 22 will yieldingly hold the lever either out of working position in alignment with the clamping face of jaw 2, or upwardly against flange 13 of body A.

The movable jaw 3 is also arranged to support a hook or supporting member 23 which is pivotally connected thereto between ears 20, 25, by pivot pin 26. Member 23 is employed where it is desired to hook the tool to a rigid support for use in re-shaping bent curved beams. Such use of the tool is disclosed in Figure 6, the diagram of which shows tool 25 A applied to the rear horn 31 of a bent automobile frame. The jaw of the tool is rigidly clamped to the end of the horn and member 23 of the tool is pivotally connected to a rigid support 33. When tool A is 30 moved in the direction of arrow 34 the front end of the tool is caused to move in the arc of a circle to dotted line position due to the pivotal connection of the tool with support 33 and the rigid connection of the front end 35 of the tool with the horn 31. This circular movement is determined by the relative position of support 33 with respect to the tool and frame. Therefore by changing the relative position of the support with respect to 40 the tool an operator may readily utilize the tool for re-shaping bent beams on sweeping curves of varying radii. Mounting of the hook member 23 on the movable jaw 3 as shown in the drawing is preferred, where the 45 tool is to be used for re-shaping bent curved beams to curves of substantial radii.

What I claim is:

1. A frame and axle straightening tool, comprising a main body shaped at one end 50 to form a jaw, a second jaw adjustably mounted on said main body, and elongated means pivotally secured to said main body and adapted to engage the channel of an iron bar for clamping and holding the web portion of said iron bar against and parallel to the clamping surface of said second jaw without engagement of said first jaw with said iron bar.
2. A frame and axle straightening tool, comprising a main body shaped at one end 55 to form a jaw, a second jaw adjustably mounted on said main body, and supporting means pivotally secured to said tool for piv- 60 tally attaching said tool to a support while

re-shaping curved bent beams to varying radii.

3. A frame and axle straightening tool, comprising a main body shaped at one end 70 to form a jaw, a second jaw adjustably mounted in said main body and co-operating with said first jaw and elongated means pivotally connected with said first jaw adapted to engage the inside of a channeled iron bar and force same against the main body 75 of the tool and said second jaw parallel to the clamping surface thereof, without engagement of said first jaw with said bar.

4. A frame and axle straightening tool, comprising a wrench having a fixed and a 80 slidable jaw, means pivotally connected to the body of said wrench, co-operating with said slidable jaw in rigidly holding a channel bar parallel to the clamping surface of 85 said slidable jaw, and means pivotally connected to said slidable jaw for pivotally supporting said tool when gripping a bent beam to effect movement of said tool on a circle around its support during reshaping 90 operations of said beam.

5. A frame and axle straightening tool, comprising a main body provided with 95 ratchet teeth and a series of circular recesses and shaped at one end to form a jaw, a second jaw adjustably mounted on said main body and co-operating with said first jaw, and elongated means pivotally connected with said first jaw adapted to engage the inside of a channeled iron bar and force same against the main body of the tool and 100 said second jaw parallel to the clamping surface thereof, said second jaw including at oppositely arranged sides pawls adapted to engage the ratchet teeth of said main body and additional locking means co-operating with said circular recesses in said main body.

In testimony whereof I affix my signature.

GUY A. COUNTRYMAN.
